Hans Leitner

UNITED STATES PATENT OFFICE.

HENRY LEITNER, OF LONDON, ENGLAND.

METAL AIR PROPELLER AND THE LIKE.

Original application filed January 21, 1922, Serial No. 530,845. Divided and this application filed May 3, 1924. Serial No. 710,839.

To all whom it may concern:

Be it known that I, HENRY LEITNER, a subject of the King of Great Britain, residing at Regent House, Kingsway, London, 5 England, have invented new and useful Improvements in Metal Air Propellers and the like, of which the following is a specification.

My invention has reference to screw-propellers, mainly for use on aircraft, of the kind described in my prior Patent No. 1,500,606 of July 15, 1924, of which this is a division, and in which the blades are hollow and made of sheet metal, and which are advantageously detachable from the propeller hub and adjustable therein for variations of pitch and consequently vary from an aerofoil cross section in the body to a circular cross section at the root.

According to the invention the blade is made from sheet metal folded to form the edges of the blade and joined at the meeting edges by a longitudinal mechanical seam extending along one side of the blade intermediate of the two folded edges. Or, the blade may be made in two sections, one or the main section of which is folded to form both edges of the blade, whilst the other section is joined to the aforesaid section by longitudinal mechanical seams extending along one side of the blade intermediate of the two folded edges.

To enable the invention to be fully understood I will describe it by reference to the accompanying drawing, in which which:—

Figure 1 is an elevation of a hollow sheet metal propeller blade of the type having a cylindrical stem or root designed to turn in a bearing in the propeller hub for varying 40 the pitch, the said blade being constructed in accordance with the invention.

Figure 2 is a cross section on the line 2—2, Figure 1, but drawn to a larger scale, and

Figure 3 is a partial cross section on the 45 line 3—3, Figure 1, also drawn to a larger scale.

Figure 4 is a view similar to Figure 2, illustrating a modification and

Figure 5 is a view corresponding to a section taken on the line 3—3, Figure 1, of the 50 modification shown in Figure 4.

Figures 6 and 7 are sections illustrating

modifications of the joint in the blade illustrated in Figures 2 and 3.

Figure 8 is a similar view to Figure 6 of 55 a modified joint and

Figure 9 is a similar view to Figure 8 but taken near the root of the blade.

Figure 10 is a modification of the joint shown in Figure 9. 60

Referring to Figures 1 and 2, *a* is the sheet of metal folded to form the edges of the propeller blade and *c*, *d* are the respective bends therein constituting the leading and trailing edges of the blades, the meeting edges of the sheet overlapping at about the centre of the blade and being secured by rivets *e*; or, they may be secured by other means. Figure 2 is a section through the top of the blade where only one lamina is 65 employed, whilst Figure 3 is a partial section nearer the root of the blade where, say, two additional laminae are used, the overlapping joint being arranged as indicated, whereas, where all the laminae enter the cylindrical casing *f* forming the stem, the rivets *e* may also pass through the said casing. 70

Figures 4 and 5 show the two-part construction of blade in which both the joints, 80 which are shown of the overlap type, are confined to one face of the blade, *a* indicating one part of the blade and *b* the other part.

Instead of the overlapping joints described with reference to Figures 1 to 3, the meeting edges of the part *a* (or of the parts *a* and *b*) may butt together, as indicated in Figures 6 and 7, the joints being covered by metal strips *g* secured to the said parts *a* and *b* by rivets *h*. Or, other means than 90 rivets may be employed.

Figures 8, 9 and 10 show different forms of folded or tinsmith's joints for uniting the edges of the parts *a* and *b*, that illustrated in Figure 8 showing the edges of the 95 said parts folded together, the inner laminae in Figure 9 being riveted to the said jointed outer lamina by rivets *i*. Figure 10 shows a metal strip *j* intermediate of the adjacent edges of the parts *a* and *b* and having the edges connected thereto by folded or tinsmith's joints. 100

Claims:

1. A screw-propeller blade of the kind de-

scribed, formed from sheet metal folded to form the edges of the blade and joined at the meeting edges by a longitudinal mechanical seam extending along one side of the 5 blade intermediate of the two folded edges.

2. A screw-propeller blade of the kind described, formed from two sections of sheet metal, one section of which is folded to form both edges of the blade, whilst the other section 10 is joined to the aforesaid section by longitudinal mechanical seams extending

one side of the blade intermediate of the two folded edges.

3. A screw-propeller blade of the kind described, formed from two sections of sheet 15 metal, the main section of which is folded to form both edges of the blade, whilst the intermediate section is jointed to the main section by longitudinal mechanical seams extending along one side of the blade intermediate of the two folded edges. 20

HENRY LEITNER.
